UNITED STATES PATENT OFFICE.

JOHN C. DOANE, OF EAST HARTFORD, CONNECTICUT, ASSIGNEE TO UNDERWOOD
TYPEWRITER COMPANY, OF NEW YORK, N. Y., A CORPORATION OF DELA-
WARE.

TYPEWRITING-MACHINE.

1,284,123.

Specification of Letters Patent. Patented July 12, 1921.

Application filed December 11, 1918. Serial No. 266,200.

To all whom it may concern:

Be it known that I, JOHN C. DOANE, a citizen of the United States, residing in East Hartford, in the county of Hartford 5 and State of Connecticut, have invented certain new and useful Improvements in Type-writing-Machines, of which the following is a specification.

This invention relates to typewriting machines and is herein disclosed as applied to the platen scale of an Underwood typewriting machine, and is in the nature of an improvement on my application, Serial No. 265,325, filed December 5, 1918. In said 15 application, there is disclosed a platen scale which is adapted to rise with the shifting platen of the Underwood typewriting machine, so that the scale bears the same relation to the writing line both in the upper 20 and lower positions of the platen, the scale being resiliently mounted on swinging brackets, each having one edge adjacent the platen, said brackets adapted to swing so that their said edges follow the platen fairly 25 closely.

In the present disclosure, means are provided to enable the platen scale to form part of a unitary bar or device which extends across the machine adjacent the top of the 30 segment, and is adapted to have both ends moved simultaneously. To maintain the scale near the platen, brackets may be provided on the usual segment adapted to carry swinging arms, so that the latter may hold 35 the scale against the platen.

Other features and advantages will hereinafter appear.

In the accompanying drawings,

Figure 1 is a perspective view of an Underwood typewriting machine showing my invention as applied thereto.

Fig. 2 is a sectional side view of the same, many parts being shown diagrammatically, or being omitted.

Fig. 3 is a side view, partly in section, similar to Fig. 2, but showing the platen in its upper-case position.

In the Underwood typewriting machine, character keys 1, when depressed, carry 50 down their key-levers 2, thereby swinging sub-levers 3 to carry type-bars 4 upwardly and rearwardly, so that lower-case types 5 and upper-case types 6 on the type-bars will print against the front side of a platen 7, 55 which is rotatably mounted in the platen

frame 8. The platen frame forms part of a carriage 9, said carriage having pivoted thereon a rack 10 meshing with a pinion 11, connected to an escapement wheel 12, so that the carriage may be fed along thereby 60 to the left at each actuation of any key 1, there being provided for this purpose the usual dogs 13 and the spring barrel (not shown). In order to actuate the dogs 13, 65 there is a universal bar 14 fast to a segment 15, which is adapted to be struck by heels 16 on the type-bars 4 as they approach the platen, and thereby vibrate the dogs rearwardly.

Writing is normally done with the lower-case type 5. When it is desired to write in upper case, a shift-key 17 on the front end of a key-lever 18 is depressed, so that an upstanding arm 19, at the rear end of its lever, will rock a bell-crank 20, forming 70 part of a frame which also includes the carriage-shift rail 21. When a key is thus depressed, to lift the rail 21, the platen frame 8 is shifted upwardly, because it runs by a wheel 22 on the rail 21, and is guided in vertical direction by the usual arms 23 journaled at 24 at the rear of the carriage 9. 75

In order to enable the typist to quickly and accurately identify the position of the characters written on a work-sheet passed 80 around the platen 7, there is provided a scale-plate 25, adjacent the platen and graduated at letter-space intervals to correspond to the spacing of the front scale 26. The scale-plate 25 is relatively short and 85 comprises two wings extending on either side of a slot 27 at the type-guide 28, the slot being deep enough to allow the lower-case type 5 to be clear of the scale-plate 25 when writing in upper-case position. 90

To enable the scale 25 to rise with the platen when the latter is raised by the rail 21, the bell-crank 20 is provided with a plate 29 on which is fast a forwardly-extending arm 30 connected to the dependent arm 100 31 of a long transverse bail-like member 32, which includes the scale 25, the connection including a link 33 pivoted to a guide arm 34 which latter is pivotally mounted at 35 on a bracket 36. To enable both ends 105 of the bail or member 32 to be raised at once, there is a bell-crank 20 at the other end of the machine, which may be precisely like the first bell-crank, and also provided with an arm 30 connected by a link 33 to 110

raise a second dependent arm 31 of the bail or member 32. The member 32, as herein disclosed, is not formed as a continuous integral member, but, in addition to the two dependent arms 31, includes a left-hand rod 37 and a right-hand rod 38, each of said rods being held by a pair of screws 39 to offset ears 40 on the scale-plate 25. The rods 37 and 38 lie along or just back of the top of the segment 41, and the offset ears 40 are provided in order to enable the scale-plate 25 to be located in its proper position behind the type-guide 28 adjacent the platen.

In order to hold the scale-plate 25 in position adjacent the platen and to keep it clear of the type-guide 28 and the ribbon-carrier 42, there are provided a pair of pivoted arms 43, which are adapted to bear against the rods 37 and 38, respectively, and hold the scale-plate 25 against the platen. To enable the arms 43 to do this, each arm is shown as comprising a small end projection 44 adapted to enter an opening 45 in its rod 37 or 38, and bearing against the edge of that opening by a heel 46, which may be cam-shaped, if desired, in order to make it bear properly against the rod 37 or 38, as the case may be. In order that the scale-plate 25 may move substantially vertically with the platen, which itself moves vertically, the arms 43 are pivoted on forwardly-projecting brackets 47 having downwardly-projecting ears 48, which are screwed to the face of the segment 41, and which have upturned ears 49 into which are threaded shouldered screws 50 adapted to form pivots for the arms 43. In order to make of each dependent arm 31, taken with its adjacent arms 34 and 38, a quasi-parallel motion device, the brackets 36 on which the arms 34 are pivoted extend rearwardly from the inner face of the machine frame to which they are held by screws 51, so that the pivots 35 are nearly below or slightly in front of the pivots 50. In order to provide for an adjustment of the length of the swing arms 34 to vary the angle of the link 33, the arms 34 may be formed of two pieces 52 and 53, and be held together by screws 54 threaded into the member 53 and adapted to pass through elongated slots 55 in the member 52. Such an adjustment is possible because the links 33 may be nearly vertical, and, therefore, allow for considerable adjustment to and from the arms 34. Since the vertical arms 31 are pivoted on screws 56 threaded into the members 52, the member 53 is provided with an additional slot 57 to prevent the pivot 56 from interfering with the aforesaid adjustment. Since the bail member 32 is long, and preferably rather light, and includes an offset bend 58 at each end to bring the scale to proper position, the bail member is provided with means adapted to resist the shock of a work-sheet which may be

doubled upon the platen, so that it strikes the scale-plate 25 with considerable force, said means being adapted more especially to prevent endwise movement of the scale.

In the present disclosure, this means for receiving the shock is shown as a link 59 pivoted on an ear 60 of the bail member 32, said link extending to the adjacent bracket 47 to which it is pivoted by an upturned ear engaged by a headed screw 61. The link 59 has its pivots 60 and 61 so related that they cause the scale-plate 25 to bear the same relation to the type-guide in both its upper and lower positions. To effect this, the pivot 60 is somewhat below the pivot 61 in the lower-case printing position.

Variations may be resorted to within the scope of the invention, and portions of the improvements may be used without others.

Having thus described my invention, I claim:

1. In a typewriting machine, the combination with a platen and a shift-frame therefor, of a type-guide, a scale extending across the type-guide between the platen and the type-guide and having depending arms, linkages between said shift-frame and said arms for shifting said scale correspondingly when said platen is shifted, and a link pivoted to the frame of the machine and connected to the scale for guiding the scale relatively to the platen.

2. In a typewriting machine, the combination with a shiftable platen, a scale and a shift-frame therefor, of arms pivoted at the front of the machine for holding the scale against the platen, a link connected to the shift-frame, a second arm pivoted to the link, and dependent arms connected to the pivoted arms and fast to the scale to cause the shifting frame to shift the scale with the platen.

3. In a typewriting machine, the combination with a shiftable platen, a scale and a shift-frame therefor, of arms pivoted at the front of the machine for holding the scale against the platen, links connected to the shift-frame, second arms pivoted to the links, dependent arms connected to the second arms and fast to the scale to cause the shifting frame to shift the scale with the platen, and a link pivoted to said scale adapted to hold the scale against traveling with the platen.

4. The combination with a typewriting machine, of a platen, a shift-frame therefor, arms at each end of the machine and pivoted at the front of the machine, depending arms connected to the pivoted arms, a scale fast to the depending arms, and a connection from the shift-frame to the depending arms.

5. In a typewriting machine, the combination with a platen and a shift-frame therefor, of a scale, arms pivoted at the front of

the machine, adjustable links connecting the shift-frame to the arms, other arms pivoted at the front of the machine, and rods fast to the scale and having depending arms connecting said pivoted arms and forming a quasi-parallel motion device with the pivoted arms.

6. In a typewriting machine, the combination with a platen, of a shift-frame having 10 ends, a scale, rigid extensions of said scale extending to points adjacent the ends of the frame and including depending arms, means connecting the arms to the frame, and means for guiding the scale.

15 7. In a typewriting machine, the combination with a platen, of a shift-frame having ends, a scale, rigid extensions of said scale extending to points adjacent the ends of the frame and including depending arms, a second set of arms pivoted to the machine frame, said second arms being pivoted to 20 said depending arms, and links connecting the second arms to the shift-frame.

8. In a typewriting machine, the combination with a platen, of a shift-frame having 25 ends, a scale, rigid extensions of said scale extending to points adjacent the ends of the frame and including depending arms, means connecting the arms to the frame, 30 and guide arms pivoted to the frame of the machine at the front to guide the scale.

9. In a typewriting machine, the combination with a platen, of a shift-frame having 35 ends, a scale, rigid extensions of said scale extending to points adjacent the ends of the frame and including depending arms, a second set of arms pivoted to the machine frame, said first arms pivoted to said second arms, links connecting the second arms 40 to the shift-frame, and guide arms pivoted to the frame of the machine at the front to guide the scale.

10. In a typewriting machine having a platen, the combination with a segment, of 45 bracket arms projecting forward from the segment, swinging arms pivoted at the ends of the bracket arms, a scale held adjacent the platen by the swinging arms, a shift-frame comprising ends, and a linkage from 50 each end of the shift-frame connected to the scale to cause the scale to shift with the shift-frame.

11. In a typewriting machine having a platen, the combination with a segment, of 55 bracket arms projecting forward from the segment, swinging arms pivoted at the ends of the bracket arms, a scale held adjacent the platen by the swinging arms, a shift-frame comprising ends, guide arms also 60 pivoted at the front of the machine, said scale having depending arms extending from the swinging arms to the guide arms, and links connecting the guide arms to the shift-frame.

65 12. In a typewriting machine, the combina-

tion with a segment, of bracket arms projecting from said segment near the printing point, a shiftable platen, swinging arms pivoted on the bracket arms, a scale held adjacent the platen by the swinging arms, 70 means for shifting said swinging arms in unison with the shifting platen, and a link for holding the scale against endwise movement.

13. In a typewriting machine having a 75 platen, the combination with a segment, of bracket arms projecting forward from the segment, swinging arms pivoted at the ends of the bracket arms, a scale held adjacent the platen by the swinging arms, a shift-frame comprising ends, and a linkage from 80 each end of the shift-frame connected to the scale to cause the scale to shift with the shift-frame.

14. In a typewriting machine having a 85 platen, the combination with a segment, of bracket arms projecting forward from the segment, swinging arms pivoted at the ends of the bracket arms, a scale held adjacent the platen by the swinging arms, a shift-frame comprising ends, guide arms also pivoted at the front of the machine, links 90 extending from the swinging arms to the guide arms, links connecting the guide arms to the shift-frame, and a link for holding the scale 95 against endwise movement.

15. In a typewriting machine having a platen, the combination with a segment, of 100 bracket arms projecting forward from the segment, swinging arms pivoted at the ends of the bracket arms, a scale held adjacent the platen by the swinging arms, a shift-frame comprising ends, a linkage from each 105 end of the shift-frame connected to the scale to cause the scale to shift with the shift-frame, and a link pivoted to the segment and a scale arm to hold the scale against endwise movement.

16. In a typewriting machine having a platen, the combination with a segment, of 110 bracket arms projecting forward from the segment, swinging arms pivoted at the ends of the bracket arms, a scale held adjacent the platen by the swinging arms, a shift-frame comprising ends, guide arms also pivoted at the front of the machine, links 115 extending from the swinging arms to the guide arms, links connecting the guide arms to the shift-frame, and a link pivoted to the segment and a scale arm to hold the scale 120 against endwise movement.

17. In a typewriting machine, the combination with a platen and a shift-frame therefor, of a type-guide, a scale extending across the type-guide between the platen and the type-guide and having depending arms, linkages between said shift-frame and said arms for shifting said scale correspondingly when said platen is shifted, a link pivoted 125 to the frame of the machine and connected 130

to the scale for guiding the scale relatively to the platen, and a second link pivoted at one end on the scale and pivoted at its other end on the frame of the machine to prevent 5 endwise movement of the scale.

18. In a typewriting machine, the combination with a platen and a shift-frame therefor, of a type-guide, a scale extending across the type-guide between the platen and 10 the type-guide, arms fast to said scale for supporting it, a link extending from each of said arms to the shift-frame, guides for causing the scale as it shifts to shift with the platen, a link pivoted to the scale, and a 15 fixed pivot for said last-named link to enable the link to hold the scale against endwise movement.

19. In a typewriting machine having a platen and a shift-frame comprising ends, 20 the combination with a scale adjacent said platen, means for mounting said scale independently of said platen, said means comprising a parallel-motion linkage at each end of the scale, and a link connecting each 25 of said linkages to the corresponding end of the shift-frame to raise said scale when said frame is shifted.

20. In a typewriting machine having a platen and a shift-frame comprising ends, 30 the combination with a segment, of brackets fixed to said segment, a scale adjacent said platen, means for mounting said scale independently of said platen comprising a parallel-motion linkage at each end of the scale, 35 said linkages each comprising a link pivoted to the frame of the machine, a second link pivoted at one end to the first link and fixed to the scale at its other end, a third link pivoted at one end to a bracket on the segment and projecting through said second link at its other end, and a link connecting each of said linkages to the corresponding end of the shift-frame to raise said scale when said frame is shifted.

40 21. In a typewriting machine having a platen and a shift-frame comprising ends, the combination with a segment, of brackets fixed to said segment, a scale adjacent said platen, means for mounting said scale independently of said platen comprising a parallel-motion linkage at each end of the scale,

55 said linkages each comprising a link pivoted to the frame of the machine, a second link pivoted at one end to the first link and fixed to the scale at its other end, a third link pivoted at one end to a bracket on the segment and projecting through said second link at its other end, a link connecting each of said linkages to the corresponding end of the shift-frame to raise said scale when said frame is shifted, and means for varying the length of the link pivoted to the frame of the machine to vary the amount of shift of the scale.

22. In a typewriting machine having a 65 platen and a shift-frame comprising ends, the combination with a segment, of brackets fixed to said segment, a scale adjacent said platen, means for mounting the scale independently of said platen comprising a parallel-motion linkage at each end of the scale, 70 said linkages each comprising a link pivoted to the frame of the machine, a second link pivoted at one end to the first link and fixed to the scale at its other end, a third link pivoted at one end to a bracket on the segment and projecting through said second link at its other end, a link connecting each of said linkages to the corresponding end of the shift-frame to raise said scale when said 75 frame is shifted, and another link pivoted at one end to said second link and pivoted at its other end to one of said brackets to prevent endwise movement of the scale.

23. In a typewriting machine having a 80 platen, the combination with a segment having brackets thereon, of a scale adjacent said platen, a shift-frame comprising ends, and means for shifting the scale when said platen is shifted and guiding the scale relatively to the platen, said means comprising links pivoted to the frame of the machine, 85 second links connecting the first links to the ends of the shift-frame, depending members fixed to the scale and pivoted on said first 90 links, and third links pivoted on the brackets on the segment and projecting through the depending members.
